[57] CLAIM

The ornamental design for a bottle, substantially as shown and described.

DESCRIPTION

FIG. 1 is a top plan view of a bottle, showing my new design;

FIG. 2 is a front elevational view thereof;

FIG. 3 is a bottom plan view thereof;

FIG. 4 is a side elevational view thereof, viewed from the right of FIG. 2, the opposite side elevational view being the mirror image thereof; and

FIG. 5 is a rear elevational view thereof.
